SAFETY RAZOR

Frank Henry Eve and Albert Edward Clarke,
Luton, EnglandApplication May 21, 1943, Serial No. 487,928
In Great Britain July 20, 1942

9 Claims. (Cl. 30—50)

This invention relates to safety razors in which a double-edged blade is clamped in a holder comprising a guard, a rigid backing and a handle. Hitherto the blades of such razors have been of the wafer type. Such blades are considered unsuitable for heavy beards, for which the so-called solid or hollow-ground blade is preferred, which blades however have only one edge. It has been proposed to make double-edged blades of the solid, hollow-ground type for use with holders of the kind in question, but so far as we are aware such blades have never come into use.

It is an object of this invention to provide a double-edged hollow-ground blade suitable for use in a holder of the kind set forth.

It is another object of the invention to provide a hollow-ground blade which will readily adjust itself to the convex surface of a double-edged guard of a holder.

A further object of this invention is to provide an improved safety razor for the reception of our new blade.

Our new blade comprises two components each having a cutting edge and hinged together at the edges opposite to the cutting edges, so as to constitute a single double-edged blade which can fold about its median line, each component being of the solid hollow-ground type.

The thick edges of the components may be cut away in the manner of the leaves of a door hinge, one of them having a central lug fitting between two lateral lugs on the other, the three lugs being bored to receive a hinge pin or pins. It will be seen that such a hinged blade can adjust itself to the convex surface of the double-edged guard of a holder similar to that commonly used for double-edged wafer blades, the rigid backing being made somewhat deeper to accommodate the thickness of the improved blade at its center.

Referring to the accompanying drawing, Figure 1 is a plan of a razor blade according to this invention;

Figure 2 is an end elevation of the blade; Figure 3 is an end elevation of the complete razor with the blade in place;

Figure 4 is a perspective view of the blade;

Figure 5 is a perspective view of the guard forming part of the holder;

Figure 6 is a fragmentary view in section of the handle;

Fig. 7 is a perspective view of the complete device as shown in Fig. 3.

Referring first to Figures 1 and 2, one component 10 of the blade is cut away at its thick edge to provide a lug 12 and the other component

14 is cut away to provide two lugs 16 which straddle the lug 12. The three lugs are bored to receive hinge pins 18 which are fixed rigidly in the lugs 16, the component 10 being able to turn freely on these pins. Part of the central lug 12 is cut away, as is part of the component 14, so as to form an opening 20 through which a screw 22 fixed to the backing 24 may project. The sides of this hole 22 are flared or tapered on both sides of the lug to enable the screw 22 to pass through the hole whichever side of the composite blade is against the guard 26 and to allow the blade to conform to the curve of the holder.

As will be seen from Figure 3, the holder is similar to the well-known Gillette holder, consisting of a guard 26, the backing 24 with its screw 22 and a handle 28 having a screw-threaded hole 30 (Figure 6) to receive the screw 22. The backing 24 is deeper and curved to a smaller radius than that of the customary holder for use with wafer blades, this being necessary on account of the greater thickness of the central portion of the improved blade.

The blade is assembled with the razor in the same manner as the ordinary double-edged wafer blade. It is held with its edges parallel to the edges of the guard 26 by two tongues or projections 32 which enter notches 34 in the lugs 16. As will be clear from Figure 4, the notches are formed by removing a short length (for example one-eighth of an inch) of the end of each of the lugs 16 and of the hinge pins 18. Each notch is closed on one side by the edge of the cut-away portion of the blade component 10 and the other side of the notch is so located that the edges of the notch lie symmetrically on opposite sides of the centre line when the blade is in contact with the concave side of the guard. As the notch is symmetrical either side or face of the blade may be in contact with the guard.

In order to ensure that the razor shall not be used if by inadvertence the blade is assembled with the guard in an oblique or skew position, the screw-threaded hole 30 is counter-bored for a portion of its length as indicated at 36. If the blade is not square with the guard, the projections 32 will not enter the notches 34 and they will hold the blade out of contact with the guard. Consequently, the screw 22 will not project from the underside of the guard to its full extent, and the length of the screw is so adjusted that in these conditions the screw does not enter the screw-threaded portion of the hole 30. Thus the handle cannot be screwed on to the screw and the user is

made aware that he has assembled the blade incorrectly.

The recesses 34 also serve to locate the blade in the holder of a sharpening device, such for example as one of the rotary type described in the specification of our British Patent No. 540,853.

We claim:

1. A safety-razor blade comprising two components of the solid hollow-ground type each having a cutting edge and hinged together at the edges opposite to the cutting edges to constitute a single double-edged blade which can fold about its median line.

2. A safety-razor blade comprising two components of the solid hollow-ground type each having a cutting edge, the thick edges of said components being cut away to form hinge lugs, and pivot means interconnecting said lugs.

3. A safety-razor blade comprising two components of the solid hollow-ground type each having a cutting edge, one of said components being formed at its thick edge with a hinge lug and the second of said components being formed at its edge with two hinge lugs spaced apart from one another and embracing said first lug, and pivot means interconnecting said first lug with each of said other lugs.

4. A safety-razor blade as defined in claim 3 wherein said first lug is formed with a transverse opening to receive a screw projecting from a backing member of a safety razor.

5. A safety razor comprising a guard and a backing member and a blade held between said guard and said backing member, said blade comprising two components of the solid hollow-

ground type each having a cutting edge and hinged together at the edges opposite to the cutting edges to constitute a single double-edged blade which can fold about its median line.

5 6. A safety razor as defined in claim 5 wherein said guard is formed at each end with a projection and said blade is formed at each end with a recess, said recesses and projections being complementary to one another and adapted to locate said blade accurately in position on said guard.

7. A safety razor comprising a guard, a backing member, a handle and a double-edged hollow-ground blade, said guard and said blade being formed with complementary locating projections and recesses, said backing member bearing a screw for engagement with said handle, and said handle having a bore that is internally screw-threaded to engage said screw but the entrance of which is unthreaded for a distance sufficient to prevent said screw engaging said thread in the event that said projections and recesses are not in engagement with one another.

8. A safety-razor blade comprising two components of the solid hollow-ground type each having a cutting edge and hinged together at the edges opposite to the cutting edges.

9. A safety razor comprising a guard and a backing member and a blade held between said guard and said backing member, said blade comprising two components of the solid hollow-ground type each having a cutting edge and hinged together at the edges opposite to the cutting edges.

FRANK HENRY EVE.
ALBERT EDWARD CLARKE.
